UNITED STATES PATENT OFFICE.

EDWARD CLIFF, OF NEWARK, NEW JERSEY.

HOSE-REEL.

SPECIFICATION forming part of Letters Patent No. 601,633, dated April 5, 1898.

Application filed October 18, 1897. Serial No. 655,547. (No model.)

To all whom it may concern:

Be it known that I, EDWARD CLIFF, a citizen of the United States, and a resident of Newark, in the county of Essex and State of New Jersey, have invented certain new and useful Improvements in Hose-Reels, of which the following is a specification.

The invention relates to improvements in hose-reels, and particularly to improvements in hose-reels of the character employed in buildings having a fixed water-supply apparatus, to which the hose or the reel may be permanently applied.

In the embodiment of my invention herein presented the reel proper is connected to the stem of the valve controlling the flow of water, and said valve is opened by the unwinding of the hose from the reel, so that upon the hose being unwound for use the water is automatically turned on and is within the hose as soon as the latter can be used. When fully unwound, the hose is entirely free of the reel and is simply left connected with the exposed water-supply apparatus. After the use of the hose in extinguishing a fire the reverse motion of the reel without regard to the hose will close the valve in the water-supply pipe and thereafter at any convenient time by disconnecting the reel from the valve-stem, but leaving said reel to turn freely around said stem or upon a sleeve inclosing said stem, the hose may be readily rewound upon the reel without affecting the valve.

The invention will be fully understood from the detailed description hereinafter presented, reference being had to the accompanying drawings, in which—

Figure 1 is a central vertical longitudinal section through a reel and water-supply apparatus embodying the invention, the valve controlling the flow of water being shown in its closed position and the hose being omitted from the water-supply pipe. Fig. 2 is a side elevation, partly broken away, of a reel and hose embracing the invention. Fig. 3 is an enlarged detached side elevation of a portion of the reel; and Fig. 4 is an edge view showing the reel mounted at an angle of forty-five degrees instead of on a horizontal plane, as indicated in Fig. 1.

In the drawings, A designates the reel,

which is composed of the hub B and disks C C, the latter being secured to the flanges E of said hub by means of the bolts E, upon which the hose F is wound, as more clearly illustrated in Figs. 2 and 4. The hub B is of cast metal and contains the circular hollow bore G to receive the sleeve H, which incloses the valve-stem I and is connected with the valve-casing J, the latter being supported upon the water-supply pipe K. The hub B is cast with the radial end flanges D and with the webs L, which connect the said flanges within the line of the bolts E, as indicated in Fig. 1. The plates or disks C C have central apertures, as shown, the disk nearest to the valve-casing J having its central aperture of greater diameter than the bore G of said hub B, while the disk C at the outer side of the reel has its central aperture of a diameter adapted to snugly receive the outer end of the said hub B. The outer end of the hub B has the inwardly-projecting annular flange M, which is utilized, as hereinafter described, for fastening the reel A and sleeve R together, so that the movement of the reel turning on the sleeve H will effect the longitudinal movement of the valve-stem I.

The valve-casing J, the water-pipe K, and the valve N are of well-known form, said valve-casing, as usual, receiving the sleeve H and being provided with the nozzle O, to which the hose F is attached. The sleeve H at one portion has a bore which is polygonal in cross-section to engage the polygonal portion of the valve-stem I, and the bore of said sleeve H at its other portion is circular in cross-section to receive and permit the revolving therein of the inner end of the sleeve R, which, as shown in Fig. 1, is internally threaded and receives the exterior thread formed on the valve-stem I. The sleeve R is keyed by means of the pins S within the sleeve H, the purpose of the pins being merely to prevent the sleeve R from traveling outward from the sleeve H when said sleeve R is being revolved under the action of the reel A. The sleeve R has within the bore G of the hub B the annular flange T, which, as shown in Fig. 1, is at the inner side of the flange M, formed on the reel, and the outer end of the sleeve R is externally threaded to receive the clamp-

ing-nut V and jam-nut W. When the parts are in the position in which they are shown in Fig. 1, the sleeve R is connected with the reel A by means of the pressure exerted on the flange M by the nut V and flange T, and under such condition the sleeve R will freely revolve with the reel A and by means of its internal thread effect the longitudinal movement of the valve-stem I and valve N, said stem I being prevented from rotating by the polygonal form of the bore of the sleeve H and the corresponding form of the polygonal portion of said valve-stem. Thus upon the rotation of the reel A, when the parts are in the condition shown in Fig. 1, the sleeve R will effect the longitudinal movement of the valve-stem I, and the latter will be held against rotation. The sleeve H is stationary and the sleeve R revolves within the outer end of the sleeve H and upon the threaded portion of the valve-stem I. Upon the outer face of the outer disk C is provided a plate X, whose central portion extends inward upon the flanges M. For convenience the tightening up of the nut V draws the head T of the sleeve R against a portion of the hub B, said portion being lettered m, but it is apparent that the flange M may be omitted and the head T drawn against the plate X, if preferred. The flange M forms a convenient means for clamping the reel and sleeve R together. When the nuts V W are loosened on the outer end of the sleeve R, the reel A is left free to revolve upon the sleeve H without in any manner affecting the valve-stem I.

The hose F is at one end provided with the usual nozzle a and at its other end is coupled to the nozzle O, forming a part of the permanent water-supply apparatus. In winding the hose upon the reel, one end of the hose being coupled to the nozzle O, the hose at about its center will be folded upon a cylinder or core of the kind shown in Letters Patent of the United States No. 585,861, granted to myself July 6, 1897, and the said cylinder or core will be placed within one of the spaces between the webs L of the hub B, and thereupon the hose will be wound upon the bolts I in double layers, the discharge-nozzle a being left in close proximity to the reel A. The hose F will preferably be wound upon the reel A when the latter is upon the sleeve H and the nut V is loosened from the outer disk C, in which condition the reel A is free to be revolved in either direction without affecting the valve-stem I. The hose being wound upon the reel A, the latter will be secured to the sleeve R by the tightening of the nut V against the inwardly-extending flange M of the reel, and upon this being done the reel may be left until occasion shall arise requiring its use.

In the employment of the apparatus for the extinguishing of a fire the attendant will seize the nozzle a and carry the same toward the fire, this action of pulling on the hose causing the reel to unwind the hose and at the

same time to effect, through the sleeve R, the outward movement of the valve-stem I and valve N, whereby the water from the pipe K may pass through the nozzle O into the hose F. The hose will be drawn from the reel until all of the hose has been released therefrom and is left hanging from the nozzle O free of the reel. After the fire has been extinguished the valve N, without regard to the hose, will be closed by causing a reverse rotation of the reel A upon the sleeve H, and after the valve N has been closed the hose F may be restored to the reel A. In restoring the hose to the reel A it will first be necessary to loosen the nut V from the flange M of the reel, and thereupon the hose, at about its center, will be doubled upon itself, as before, and placed upon the reel A, which, being then free of the clamping action of the nut V, may be conveniently revolved to wind the hose upon itself without affecting the valve-stem I or valve N. After the hose has been again fully wound upon the reel A the nut V will be retightened against the flange M, and thus the reel will become restored to a condition and position in which it may be left for further use. The nut V locks a part of the reel A to the sleeve R, and the latter is keyed to the sleeve H, and thus when the nut V is tightened against the flange M the sleeve R and reel A will revolve together and cause the thread on the valve-stem to travel in the thread within the sleeve R, while at the same time said valve-stem is permitted to travel longitudinally, but prevented against rotating by means of the polygonal bore of the sleeve H. The sleeve R is directly on and carried by the valve-stem, and thus the means for connecting the reel with the valve-stem to operate the latter are wholly independent of the reel.

The reel made the subject of this application is shown in Fig. 1 upon a horizontal sleeve H and valve-stem I, as usual; but in Fig. 4 the said reel is shown set at an angle of forty-five degrees, and this feature forms a part of the present invention. When the reel A is upon a horizontal sleeve, as shown in Fig. 1, it is more or less inconvenient to draw the hose, except in two directions, one being at each side of the longitudinal center of the valve-stem; but when the reel is mounted at or about at an angle of forty-five degrees, as shown in Fig. 1, the hose may be conveniently drawn not only in the two directions at opposite sides of the valve-stem, but also in a substantially forward direction, or at right angles to the wall adjacent to which the reel may be placed. Thus the reel mounted at the angle of forty-five degrees becomes more effective under some conditions than the reel placed horizontally.

The operation of winding the hose upon the reel and of operating the valve from the reel, above explained as pertaining to the apparatus disclosed in Fig. 1, applies also to the reel illustrated in Fig. 4. In both instances the reel revolves freely upon its tubular bear-

ing, but has no traveling motion thereon, and in both instances the valve-stem travels longitudinally, but has no rotary motion.

What I claim as my invention, and desire 5 to secure by Letters Patent, is—

1. In combination with the water-supply apparatus having the valve, projecting valve-stem and exposed hose-attaching nozzle, the reel adapted to operate said stem, means connecting the reel with said stem to operate the same and the hose at one end connected with said exposed nozzle and thence, while doubled at about its center, wound upon the said reel, the said reel and the said valve-stem being 15 arranged at an angle of about forty-five degrees; substantially as and for the purposes set forth.
2. In combination with water-supply apparatus having a tubular sleeve, a valve and a 20 valve-stem projecting into said sleeve, the reel mounted to revolve upon said sleeve, means connecting said reel with the valve-stem for the purpose of operating the valve from the reel, and hose suitably wound upon 25 the reel, said valve-stem, said sleeve and said reel being arranged at an angle of about forty-five degrees; substantially as shown and described.
3. In combination with water-supply apparatus having a stationary sleeve, a valve and a 30 valve-stem projecting through said sleeve, the reel mounted to turn axially upon said sleeve, the revoluble sleeve having a threaded bore to receive the threaded portion of the 35 valve-stem, and means for connecting said revoluble sleeve to the reel; substantially as set forth.
4. In combination with water-supply apparatus having a sleeve, a valve and a valve- 40 stem projecting through said sleeve, a reel

mounted to turn axially upon said sleeve, the revoluble sleeve having a threaded bore to receive the valve-stem and provided with the flange, the nut for connecting said flange to the reel so that said reel and said sleeve R may 45 revolve together, means for preventing said revoluble sleeve from traveling longitudinally, and hose suitably wound upon said reel; substantially as set forth.

5. Water-supply apparatus having a sleeve, 50 a valve and a valve-stem projecting through said sleeve, said valve-stem having a threaded portion and a polygonal portion and said sleeve having a polygonal bore to engage the polygonal portion of said valve-stem, combined with the reel mounted to turn axially upon said sleeve, the threaded sleeve mounted to revolve axially on and receiving the threaded portion of said valve-stem, means for detachably connecting said threaded 55 sleeve to the reel in order that said reel and sleeve may revolve together, and hose suitably wound upon said reel; substantially as set forth.

6. In combination with water-supply apparatus having a sleeve, a valve and a valve-stem projecting into said sleeve, a hose-reel mounted to turn axially on said sleeve, means for connecting said reel to said stem for operating the latter and the valve, and means for preventing said stem from turning axially during its longitudinal movement; substantially as set forth.

Signed at New York, in the county of New York and State of New York, this 15th day of October, A. D. 1897.

EDWARD CLIFF.
